UNITED STATES PATENT OFFICE.

SAMUEL KELLETT, OF SAN FRANCISCO, CALIFORNIA.

DESIGN FOR CENTER-PIECE.

Specification forming part of Design No. **8,014**, dated January 19, 1875; application filed January 2, 1875.
[Term of Patent 14 years.]

No. 2.

To all whom it may concern:

Be it known that I, SAMUEL KELLETT, of the city and county of San Francisco, California, have invented and produced a new and original Design for a Center-Piece, reference being had to the accompanying photograph, and to the letters marked thereon.

My new design is in form star-shaped. The drop A is five-leaved, Grecian in style. From base of drop five radiating forms, B, extend to inner border. Each form is composed of plain bands on each side, turning into scrolls at base. A Grecian leaf fills space between bands. Stems and flowers C C C on plain ground occupy spaces between described forms

B. The inner border is composed of oval and round shaped beading D D D, continuous. The outer border is formed by bands on scrolls E E, overlaying in each change of figure. A raised panel, F, fills in between. The extreme point G is three round balls, as terminals.

Having thus described my invention, what I claim as new, and desire to secure by Letters Patent, is—

The design for center-piece, as shown and described.

SAMUEL KELLETT.
